UNITED STATES PATENT OFFICE.

EUGENE F. O'NEILL, OF MINNEAPOLIS, MINNESOTA, ASSIGNOR TO BECKWITH-O'NEILL COMPANY, OF MINNEAPOLIS, MINNESOTA, A CORPORATION OF MINNESOTA.

MOUNTING FOR SOUND-REPRODUCING MACHINES.

1,418,016.

Specification of Letters Patent. Patented May 30, 1922.

Application filed October 4, 1920. Serial No. 414,520.

To all whom it may concern:

Be it known that I, EUGENE F. O'NEILL, a citizen of the United States, residing at Minneapolis, in the county of Hennepin and 5 State of Minnesota, have invented certain new and useful Improvements in Mountings for Sound-Reproducing Machines; and I do hereby declare the following to be a full, clear, and exact description of the invention, 10 such as will enable others skilled in the art to which it appertains to make and use the same.

This invention relates to a mounting or cabinet for sound reproducing machines particularly designed to be used in sales rooms.

As is well known, the records for these machines are now sold in very large numbers. The customers purchasing the records usually wish to hear them played in the 20 sales room. It has been the common practice heretofore to provide booths in which a machine will be located and in which the customer may listen to a record played thereon. These booths are required in considerable numbers and occupy much floor space. As the sales rooms are located largely in 25 downtown stores where floor space is very expensive, the erection of a large number of these booths has become a serious item of expense. Even with a large number of 30 booths, it is often impossible to accommodate all of the customers desiring to hear a record played. It is an object, therefore, of this invention to provide a mounting for a 35 sound reproducing machine which is of small dimensions, as compared with a booth, and by means of which a customer can satisfactorily listen to the record being played without disturbing or being disturbed by an 40 other customer who is also listening to a record.

It is a further object of the invention to produce such a mounting in a simple and inexpensive manner.

45 Other objects of the invention will appear as the description proceeds in connection with the accompanying drawings, in which like reference characters refer to the same parts throughout the various views, and in 50 which

Fig. 1 is a view in front elevation of the device with some parts broken away;

Fig. 2 is a side elevation of the device, as viewed from the right of Fig. 1, also having

some parts broken away and shown in section;

Fig. 3 is a top plan view thereof;

Fig. 4 is a view mostly in section of a portion of the sound transmitting tube;

Fig. 5 is a section on the line 5—5 of Fig. 60 4; and

Figs. 6 and 7 show modifications in section of the elbow shown in Fig. 4.

Referring to the drawing, the device is seen to consist of a cabinet A comprising a 65 closed box which is adapted to contain a talking or sound reproducing machine B, and means for conveying the sound to the ears of a customer.

The cabinet A comprises front walls 1, 70 side walls 2, a bottom 3, and a top portion 4. The top portion 4 has doors 5 hinged thereon which extend for almost the full width of the cabinet and, to a considerable extent, lengthwise thereof. When these 75 doors are closed, the cabinet A forms a box which is almost, if not entirely, sound proof.

Disposed within this box is the usual sound reproducing machine B having thereon the usual turn table 6. Reproducing and sound 80 conveying arms 7, are mounted in the bracket 8. This bracket is of the same construction as that ordinarily used and attached to the sound reproducing machine itself. In the applicant's device, the position of the bracket 85 is reversed and it is attached by screws, or other suitable means, to a hollow post 9 located in the rear of the cabinet. This hollow post has a chamber 10 therein and a pipe or tube 11 is firmly secured in said post to 90 communicate with opening 10 and projects a slight distance above the top of the cabinet. A vertical tube 12 is arranged to telescope over tube 11 and to be vertically adjustable thereon. This tube 12 carries what may be 95 referred to generally as a listening device C.

This listening device C comprises the tube 12, which tube has a horizontal portion 13 extending across the top thereof and communicating therewith. Telescoping over the 100 ends of member 13 and forming a swinging joint therewith, are the elbow members 14 whose free portions project vertically. The member C has depending tubes 15 which telescope over the free ends of member 14. 105 Each of these tubes comprises a vertical portion 15^a, a curved portion 15^b which curves outwardly from member 13 and which is re-

versely curved into a U-shaped band 15°. These tubes are disposed with their bends arranged in opposite directions, so that the free ends 16 thereof approach each other, as clearly shown in Fig. 1, and are joined together at their vertical portions 15a by a connecting tube 17. Telescoping over the free end of these tubes and slidably thereon are ear pieces 18 which have sleeves 19 embracing said tubes.

Disposed in the member 13 between the members 14 is a cylindrical valve member 20 having a handle 21 thereon arranged to slide in a slot 22 in the member 13. This valve is arranged to rotate in the member 13, and as is clearly shown in Fig. 5, when the handle 21 is turned entirely to the right in said figure, will close the opening between members 13 and 12.

20 In Fig. 6, is shown a modification of the elbow member 14 and in this modification, the elbow part proper is made in a separate piece 25 and a tube 26 corresponding with the upper part of tube 14 telescoped there-over.

In Fig. 7, is shown a modification in which the tube 26 is disposed inside of an elbow member 27.

30 The usual crank for winding up the sound reproducing machine B is shown as 28, which crank projects outside of the cabinet. At one side of the machine B the cabinet A is provided with a record rack 29 in which any desired records may be kept.

35 It will be seen that the listening device C is adjustable vertically and is also adjustable axially of the tube 11, so that it can be turned thereon to any desired angle. The member 15 and members 14 can also be turned angularly on member 13, as shown in dotted lines in Fig. 2. As stated, the ear pieces 18 are also adjustable on the free ends 16 of member 15.

45 The cabinet A is provided with suitable legs 30 and the cabinets are designed to be arranged adjacent one another to form a counter, the customer's side of which is the one near the device C, while the sales side is the one disposed oppositely thereto.

50 When a customer desires to hear a record played, the device C will be adjusted so that the ear pieces 18 are brought into comfortable relation to the customer's ears. The doors 5 will then be opened and the record placed upon turn table 6 and the machine started. As the box 1 is substantially sound proof and the ear pieces 18 contact the customer's ears, practically no sound will be transmitted into the sales room and a customer will not be disturbed by other records being played, nor will the playing of the record to which he is listening disturb others.

60 The loudness of the tone of the machine can be varied by adjusting the valve 21 to suit the desire of the customer.

It is further pointed out that an important feature in applicant's device consists in the fact that the tubes conveying the sound are telescoped into each other in the direction in which the sound is to travel. In other words, 70 at every joint, the sound emerges from the inside tube into the outside tube. As a result, none of the sound volume is lost, or passes out through the telescoping joints, which loss would occur if the tubes were disposed in the reverse manner. As shown in Fig. 6, this arrangement can still be carried out by using the reduction elbow 25. In the arrangement shown in Fig. 7, the sound passes from the elbow 27, into a smaller tube 80 26. If it is desired to use an elbow of uniform dimension, as shown at 27, there will be no air or sound leakage as the joint between members 26 and 27 is a tight rigid joint. 85

If preferred, the machine B, or a series thereof, may be constructed to be driven by an electric motor, or other suitable means.

It is thus seen that applicant has produced a simple and artistic device of great utility 90 and one which can be used in a sales room and afford a great saving in floor space and expense. Generally stated, the invention consists of the structure shown and described and set forth in the appended claims. 95

What I claim is:

1. A sound reproducing machine mounting for salesrooms having in combination, a support adapted to receive the motor cabinet and turntable of a sound reproducing 100 machine, a post on said support enclosing a chamber, a tone arm mounted on said post with which said last mentioned chamber communicates, and a listening device mounted on said support and also communicating 105 with said last mentioned chamber.

2. A sound reproducing machine mounting for salesrooms having in combination, a cabinet having therein a closed chamber and constituting a support for the motor cabinet 110 and turn table of a sound reproducing machine disposed in said chamber, a member in said cabinet comprising a chamber, a tone arm mounted on said member and communicating with said last mentioned chamber and a listening device mounted on said cabinet and communicating with said last mentioned chamber.

3. A device of the class described having in combination a cabinet having a closed 120 chamber therein, said cabinet constituting a support for the motor cabinet and turntable of a sound reproducing machine, said cabinet being constructed to permit access thereto for the placing of the machine on said 125 support and the changing of records on said machine as desired in the operation of the device, a member in said cabinet having a chamber therein, a tone arm for a sound reproducing machine being mounted on said 130

member and communicating with the chamber therein, and a listening device carried by said device and communicating with said latter chamber.

5 4. The construction set forth in claim 3, said cabinet being constructed and arranged

for manipulation of said sound reproducing machine, and records therefor on one side thereof, and said listening device being disposed at the opposite side thereof. 10

In testimony whereof I affix my signature.

EUGENE F. O'NEILL.
